UNITED STATES PATENT OFFICE.

NICHOLAS NUMAJLYK, OF WINNIPEG, MANITOBA, CANADA.

CATTLE GUARD.

Application filed April 3, 1924. Serial No. 703,941.

To all whom it may concern:

Be it known that I, NICHOLAS NUMAJLYK, a citizen of Ukraine, residing at Winnipeg, in the Province of Manitoba and Dominion 5 of Canada, have invented certain new and useful Improvements in Cattle Guards, of which the following is a specification.

This invention relates to new and useful improvements in cattle guards.

10 An important object of the invention is to provide a guard that may be placed between adjacent poles of a fence adjoining railroad tracks or a highway, should the wire or the like between said posts be broken 15 down, for preventing the passage of cattle through said opening in the fence.

A further object of the invention is to provide a device of the above mentioned type which is automatic in its operation.

20 Other objects and advantages of the invention will be apparent during the course of the following description.

25 In the accompanying drawing forming a part of this specification and in which like numerals are employed to designate like parts throughout the same,

30 Figure 1 is a longitudinal sectional view of the cattle guard embodying this invention and shows the same in its inoperative position,

35 Figure 2 is a similar view to Fig. 1 with the exception that the guard is in its operative position,

40 Figure 3 is a top plan view, partly broken away, of the guard illustrated in Figs. 1 and 2,

45 Figure 4 is a detail enlarged view for showing the specific connection between the platform embodied in this invention and the support therefor,

50 Figure 5 is a rear elevational view of the guard with the various elements shown in full lines in inoperative position and in dotted lines in their operative positions,

55 Figure 6 is a rear elevational view of the guard with the various elements shown in full lines in their operative positions, and

60 Figure 7 is a top plan view of sections of railroad track and sections of fencing associated therewith with the cattle guard embodying this invention arranged to illustrate the utility for the same.

65 In the drawings, wherein for the purpose of illustration is shown a preferred embodiment of this invention, the numeral 5 designates the base or frame portion of the de-

vice embodying this invention and this base or frame portion consists of the longitudinally extending side bars 6 and the transversely extending end bars 7.

60 Rotatably journaled in the opposite, longitudinally extending side bars 6 are the transversely extending shafts 8. Eccentrically keyed to these shafts 8 are the solid, cylindrically-shaped members 9 having 65 formed therewith the upwardly extending arms 10 which are arranged in spaced relation to each other and are also spaced inwardly from the opposite ends of the solid cylindrically-shaped members 9. These separately extending arms 10 are provided with bifurcated ends 11 to which are pivotally secured the brackets 12 which are carried by the under face of the platform 13, as best 70 illustrated in Figs. 1, 2 and 4.

75 In Figs. 1 to 3 inclusive, one of the cylindrically-shaped eccentrically mounted members 9 is illustrated as being provided with a lattice work gate structure 14 which extends laterally outwardly therefrom. Secured to the opposite side rails of this gate structure 14 or preferably formed integrally therewith, are the inverted L-shaped arms 15 which extend generally upwardly therefrom and are pivotally connected at their 80 outer ends to the side bars 16. These side bars 16 are provided with T-shaped outer ends, as best illustrated in Fig. 3, and are designated by the numeral 17. Mounted upon the top faces of the longitudinally extending side bars 6 of the base frame 5 are the longitudinally slotted guides 18 which are best illustrated in Figs. 1 and 3. In Figs. 1 to 3 inclusive there is illustrated a 85 transversely extending brace rod or stop 19 which is connected at its opposite ends to the longitudinally extending side bars 6 of the base frame 5 and it will be seen by inspecting Fig. 1 that the gate 14 will rest upon this stop or cross brace 19 when the 90 platform 13 and gate structure 14 are in their inoperative positions.

95 The operation of this cattle guard will be clearly understood by a description of the device as illustrated in Figs. 1 and 2. 105 It is intended that the gate structure 14 possess a greater weight than the platform 13 and for this reason the gate 14 will overbalance the platform 13 and the various elements will normally assume the positions as 110 illustrated in Fig. 1. That is, the gate structure 14 will rest upon the stop or cross brace

19 and the platform 13 will be retained in its elevated position. If weight is applied to the platform 13 for causing the same to overbalance the gate structure 14, the platform 13 will be lowered, due to the eccentric mounting of the solid cylindrically-shaped members 9, and the gate structure 14 will be elevated into an upwardly extending position. It will be noted that the side bars 16 have also been operated by the movement of the gate structure 14 and that the T-shaped heads or ends 17 have been longitudinally moved through the slots of the guide elements 18. These side bars 16 are intended to partially close or form barriers for the sides of the platform and when combined with the gate structure 13 will substantially close off three sides of the platform 13.

It has been previously stated that Fig. 7 illustrates the utility of the device. In this figure there are illustrated the parallel tracks 20 which, of course, may be the road-bed of a highway or other public thoroughfare. Adjoining the tracks 20 are the fence structures 21 which are intended to indicate fencing around pastures or the like wherein cattle or other live stock graze. It is to be understood that these fences usually consist of uprights or posts between which strands of wire or the like are stretched. It often happens that the wires between adjacent posts will become broken down and will leave an opening through which cattle may pass. The idea embodied in this invention is to position one of the cattle guards illustrated in Figs. 1 to 6 inclusive between adjacent posts, such as indicated by the numeral A in Fig. 7, for closing the opening previously bridged by the wire strands that have been broken. It will be seen by inspecting Fig. 1 that the frame 5 will extend at right angles to the fence 21

and that the gate structure 14 will be positioned in substantially a horizontal plane or, in other words, will not fill the gap between the fence post. If, upon seeing the opening in the fence, an animal endeavors to pass through the same, it will be compelled to place its weight upon the platform 13. This weight will cause the platform to drop which will elevate the gate structure 14 and move the side bars 16 into the positions illustrated in Fig. 2. The opening through the fence will thereby be closed and the animal will not be permitted to pass therethrough. After the animal's weight has been removed from the platform 13, the overbalancing weight of the gate structure 14 will cause the platform to be elevated into the position illustrated in Fig. 1 and the gate structure 14 will return to a position resting upon the stop or cross brace 19.

It is to be understood that the form of this invention herewith shown and described is to be taken as a preferred example of the same, and that various changes in the shape, size, and arrangement of parts may be resorted to without departing from the spirit of the invention or the scope of the subjoined claim.

Having thus described the invention, I claim:

In a device of the type described, a base, a vertically movable platform carried by said base, a swinging gate carried by said base, side bars pivotally connected to said gate and slidably connected to said base, and means for causing downward movement of said platform to raise said gate for bridging one end of said platform and for operating said side bars for substantially bridging the opposite sides of said platform.

In testimony whereof I affix my signature.
NICHOLAS NUMAJLYK.
